CLAIM

The ornamental design for a pair of side shields for eyewear, as shown and described.

DESCRIPTION

FIG. 1 is a perspective view of the new design for a pair of side shields for eyewear, shown in an example eyewear environment;

FIG. 2 is a front, lateral side perspective view of the left side shield of the Pair of side shields for eyewear of FIG. 1, shown separately from the right side shield for clarity of illustration thereof;

FIG. 3 is a rear, medial side perspective view thereof;

FIG. 4 is a lateral side view thereof;

FIG. 5 is a medial side view thereof;

FIG. 6 is a top view thereof;

FIG. 7 is a bottom view thereof;

FIG. 8 is a front view thereof; and,

FIG. 9 is a rear view thereof.

The broken lines illustrate the example eyewear environment and portions of the pair of side shields for eyewear that form no part of the claimed design.

(Continued)

A left side shield is illustrated in FIGS. 2-9, it being understood that the right side shield is a mirror image thereof.
